INVENTOR:

Alfred Bayley,

BY Drake & Co. ATT'YS

UNITED STATES PATENT OFFICE.

ALFRED BAYLEY, OF NEWARK, NEW JERSEY, ASSIGNOR TO THE CENTRAL STAMPING COMPANY, OF NEW YORK.

HANDLE FOR TEA-KETTLES, &c.

SPECIFICATION forming part of Letters Patent No. 367,263, dated July 26, 1887.

Application filed October 26, 1886. Serial No. 217,217. (No model.)

To all whom it may concern:

Be it known that I, ALFRED BAYLEY, a citizen of the United States, residing at Newark, in the county of Essex and State of New Jersey, have invented certain new and useful Improvements in Handles for Tea-Kettles, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide an improved handle for tea-kettles or other purposes, to produce a more durable and effective handle, and one that will be more readily attached to the kettle or other vessel, also one that will not be heated when in use, and to reduce the cost of manufacture.

The invention consists in the improved handle and in the arrangements and combinations of parts, substantially as will be hereinafter set forth, and finally embodied in the clauses of the claim.

Referring to the accompanying drawings, in which like letters indicate corresponding parts in each of the several figures, Figure 1 is a side elevation of my improved handle. Figs. 2 and 3 are details showing certain parts of the same.

In said drawings, *a* indicates a hand-piece, preferably of wood, although porcelain or any substance that is a poor conductor of heat may be used.

b b are end caps, which are adapted to fit over the end of said hand-piece, and are provided with a suitable slot or perforation, *b'*, a seat or bearing, *b²*, and a fulcrum bearing, *b³*, to receive a tongue, *c'*, of an end piece, *c*, and are also flattened or pressed inward at one side of said perforation to provide said bearing *b²*, against which said tongue *c'* is rigidly held by the end of the hand-piece *a*. The upper portion of said end or side piece, *c*, is or may be provided with a tongue, *c'*, as aforesaid, which may extend at or approximately at right angles to the adjacent part thereof. By so forming the cap as that the lower bearing, *b²*, extends beyond the upper bearing, I secure a certain leverage on the side piece, *c*,

which prevents the weight in lifting from coming entirely on the tongue, as it would were the bearings in line, and thus allowing an easy withdrawal. By the present construction a great portion of the strain is brought to bear on the under side of the piece *c* at a little distance from the bend therein, so that withdrawal is prevented, all as will be understood. The said end piece may be curved, as indicated in Fig. 1, and is preferably made of sheet metal rolled up on the edges in the ordinary way. The edge of the lower extremity, as at *c'*, is preferably rounded, as indicated in Fig. 2, instead of being cut off square, as in other handles, thus providing a smooth rounded edge, which will not be liable to catch on the edge of the angle-piece or ear *d*, which is riveted to the kettle and in turn riveted to the handle, as will be understood. The said hand-piece *a* is or may be provided with grooves *a'* at or near the ends thereof and extending around said hand-piece, forming a shoulder. The end of said cap is rolled or pressed into said groove so as to rest against said shoulder, thus securing said cap firmly to said hand-piece and preventing withdrawal therefrom. The hand-piece extends beyond said groove *a'* and comes in contact with the tongue *c'* of said end piece, *c*, thus forcing it against its bearing in said end cap and holding said piece *c* securely in place; or, to still further strengthen the joint between said end piece, *c*, and said cap *b*, the same may be soldered, which is preferable in some instances.

I do not wish to be understood as limiting myself to the exact construction and proportion of parts herein shown, as it is evident that changes may be made in those particulars without departing from the scope or spirit of my invention.

Having thus fully described my invention, what I claim as new is—

1. In a handle for tea-kettles or other purposes, a non-heat-conducting hand-piece provided with grooves *a'*, to provide a shoulder and prevent withdrawal, end caps engaging said grooves and provided with slots or perforations *b'*, and side pieces, *c*, each provided with an upwardly-bent tongue, *c'*, all said parts being combined and arranged substantially as and for the purposes set forth.

2. In a handle, the combination, with a hand-piece, of slotted caps secured thereon and provided with bearings b^2 b^3 , the lower of which projects beyond the upper and side pieces, c , 5 provided with upwardly-bent tongues c' , said parts being arranged and operating substantially as set forth.

In testimony that I claim the foregoing I have hereunto set my hand this 20th day of October, 1886.

ALFRED BAYLEY.
